Patented Oct 24, 1922.

UNITED STATES PATENT OFFICE.

KARL F. GERHARD, OF HATTON, WASHINGTON.

PUMP.

Application filed January 21, 1922. Serial No. 530,787.

To all whom it may concern:

Be it known that I, KARL F. GERHARD, a citizen of the United States, residing at Hatton, in Adams County and State of Washington, have invented certain new and useful Improvements in Pumps, of which the following is a specification.

My present invention relates to improvements in pumps adapted especially for use in wells for elevating the water therefrom, and is of the valved reciprocating piston type, employing duplex lifting devices, in connection with which are employed a auxiliary lifting device, for increasing the lift of the water accomplished by each working stroke of the pistons. By the utilization of my invention, the pistons in their cylinders are reciprocated to lift the water column in a tubular pump casing, and by the same prime mover the pump casings are bodily lifted to elevate the water column, as will be hereinafter more specifically described.

In the accompanying drawings I have illustrated one complete example of the physical embodiment of my invention wherein the parts are combined and arranged according the best mode I have thus far devised for the practical application of the principles of my invention.

Figure 1 is a view shewing a well in section, and the duplex pump of my invention operatively applied thereto.

Figure 2 is an edge view in elevation of the operating parts of the pump.

Figure 3 is an enlarged view showing the arrangement of the lazy tong connections with the vertically reciprocable pump casings.

In the preferred form of the invention as illustrated in the drawings I utilize a pair of vertically disposed pipes or pump casings 1 and 2 that are reciprocable and connected to move in opposite directions. These casings are suspended over an equalizing wheel 3 located intermediate of the casings and provided with suitable bearings in the bearing base 4 of the pump, by means of a suspending chain 5, which at its ends is attached to collars 5' on the respective casings. The casings are thus suspended with their lower ends in the well 6 and are adapted to reciprocate vertically through openings in the top wall T of the well as seen in Figure 1. A pair of vertically disposed guide bars 7 are attached to the pump base or support 4 and extend downwardly into

the well, with guide rings 8 at their lower ends for the purpose of guiding the casings passing therethrough.

At their lower extremities the tubular pump casings are each provided with a cylinder, as 9 and 10, both of which are at all times submerged in the water of the well, and reciprocate with their casings as the latter are moved vertically in the well for lifting the water.

Within the cylinders 9 and 10 are located the usual form of lifting valves and pistons for elevating the column of water through the casings, and the pistons are actuated vertically in the cylinders by their valve rods 11, one for each piston.

The valve rods are actuated on their working strokes and lifted vertically, through the instrumentality of a combined suspending and actuating wheel or sprocket 12 and the flexible connection or sprocket chain 13 passed over and suspended on the wheel as seen in Figure 1. The wheel is located between a pair of upright posts 14 rising from the base 4, and the oscillatable shaft 15 of the wheel is journaled in the posts to oscillate and thus actuate the piston rods. The movement of the rods is simultaneous, but one rod is actuated on its working stroke while the other rod is moving on its return stroke to operate the pistons and valves in the respective cylinders 9 and 10, for the purpose of elevating the columns of water in the casings. By suitable connections from a source of power to the oscillatable arm 16 affixed to the shaft 15, the latter may be actuated to oscillate the wheel 12, and a balance wheel 17 is provided on the shaft to stabilize the movement. In this manner it will be apparent that the action of the sprocket wheel 12 and its chain 13 causes alternating lifting strokes of the pump rods 11 whereby the columns of water in the two casings are elevated, and the water eventually emerges from the upper open ends of the casings. The water is drawn in through the lower, open, valve controlled ends of the cylinders 9 and 10, in usual or suitable manner.

In addition to the lifting action of the pump rods and their pistons in the cylinders 9 and 10, the columns of water are given an auxiliary lift by bodily moving the suspended casings 1 and 2. These casings are reciprocated in synchronism with the movements of the pump rods, each casing being

elevated with the lifting stroke of its pump piston, and lowered with the return stroke of its piston, through mechanism actuated from the wheel 12 through the pump rods 11. The auxiliary mechanism includes a pair of lazy-tongs, or sets of extensible and contractible pivoted levers, the upper end of each device pivoted, as at 11^a to its pump rod, and at 20 and 21, the respective lazy-tong devices are pivoted on casings 1 and 2 at their upper ends. The lower ends of the two lazy tongs are pivoted on an equalizing lever 22, which in turn is pivoted in stationary bearings 23 in the upright posts 14. Thus at 24 and 25, the lazy tongs are pivotally connected with the equalizing lever which is adapted to oscillate in a vertical plane due to the lifting action of one of the pump rods. In Fig. 1 the pump rod 11 has been raised on its working stroke to uplifted position, and the casing 1; through the action of the lazy-tongs 18 as the latter was extended by the pull of the pump rod and pivotal connections 11^a and 20. As the lazy-tongs 18 was being extended, the complementary device 19 was contracted, through the oscillation of the equalizing lever 22, and the casing 2 thus caused to be lowered through its connection 21 with the lazy tongs 19, the different positions of the parts being indicated by dotted lines in Fig. 1, and the detail view of Fig. 3.

As thus coupled together, it will be seen that the distance of travel of the piston 35 and its pump rod is approximately twice the travel of its complementary pump casing, due to the interposition of the lazy-tongs connection between the pump rod and its casing, consequently the column of water

in the casing is lifted approximately twice 40 the height of the travel of the piston in its cylinder.

From the above description taken in connection with my drawings it will be apparent that I have provided an economical and efficient pump of this character for elevating columns of water, in which the parts are well balanced and equalized, and are operated with facility and precision to perform their required functions. 50

Having thus fully described my invention, what I claim as new and desire to secure by Letters Patent is—

1. The combination in a duplex pump with a pair of vertically reciprocable pump casings, a supporting wheel, and a suspending chain passing over said wheel having its ends connected to said casings, of pump rods in said casings, a second supporting wheel and means for oscillating said wheel, 55 a suspending chain passed over said second wheel having its ends connected to said pump rods, and connections between said rods and casings whereby the latter are alternately lifted with the alternate lifting 60 strokes of said rods.

2. The combination with a pair of vertically reciprocable pump casings and pump rods therein, of a pair of lazy-tongs each pivotally connected to a rod and a casing, 70 an equalizing lever having a stationary pivotal bearing and pivotally connected to said lazy-tongs, means for suspending the casings, an oscillatable actuating wheel, and a lift chain suspended on said wheel having 75 its ends connected to said rods.

In testimony whereof I affix my signature.
KARL F. GERHARD.
